UNITED STATES PATENT OFFICE.

LILLIAN ADAIR, OF TORONTO, ONTARIO, CANADA.

METATARSAL-ARCH SUPPORT.

1,365,645.

Specification of Letters Patent. Patented Jan. 18, 1921.

Application filed August 2, 1919. Serial No. 314,935.

To all whom it may concern:

Be it known that I, LILLIAN ADAIR, a subject of the King of Great Britain, residing at Toronto, in the county of York, Province 5 of Ontario, Canada, have invented certain new and useful Improvements in Metatarsal-Arch Supports, of which the following is the specification.

My invention relates to improvements in 10 metatarsal arch supports, and the object of the invention is to devise a support for the forward ends of the bones extending rearwardly from the metatarsal joint, thus preventing the ailment commonly referred to in 15 the medical profession as Morten's toe.

My invention consists of an insole provided on its lower face with a pad of resilient material, of preferably, semicircular shape and so situated as to raise up and support 20 the forward ends of the bones above referred to, all as hereinafter more particularly described and illustrated in the accompanying drawing in which:—

Figure 1 represents a longitudinal section 25 of a boot, and a foot therein, showing my insole and pad inserted in the boot.

Fig. 2 is an inverted plan view of an insole and pad constructed according to my invention, and

30 Fig. 3 is a cross section of my insole and pad.

Like characters of reference indicate corresponding parts in the different views.

1 is a boot, and 2 is an insole provided on 35 its lower face with a pad 3 of semi-circular shape constructed of resilient material, the curved edge of the lower surface being beveled or rounded off as illustrated, and the forward edge inclining rearwardly from the inner to the outer end of the same as shown 40 in Fig. 2. 4 is the foot, and 5 is the metatarsal joint. 6 are the rearwardly extending bones, and 7 are the forward ends thereof.

In the ailment above referred to, the forward ends 7 of the bones 6 drop and the person then walks practically on these forward ends 7 of the bones 6 which causes a very severe pain just back of the ball of the foot.

50 When my device is applied, the pad 3 raises up and retains in the correct position the forward ends 7 of the bones 6, thus restoring correct articulation, and removing the pressure on the ligaments and digital 55 nerves. The forward edge of the pad 3 is

inclined rearwardly as shown in Fig. 3 in order to conform with the inclination of the metatarsal joint, and it is not beveled or rounded but left vertical in order to impart the maximum pressure at the required point. 60

An insole provided with a pad constructed according to my invention will also, by restoring the perfect articulation of the metatarsal joint, prevent callouses forming on the ball of the foot immediately beneath the 65 metatarsal joint, which is due to pressure.

From the above description it will be seen that a device constructed according to my invention will be of great value, and will relieve considerable suffering. Moreover, it 70 is simple to construct and can be put on the market very cheaply, and there is no appreciable addition in weight which is the case with metallic supports at present in use.

What I claim as my invention is:—

1. In a metatarsal arch support, the combination with an insole, of a pad of resilient material suitably secured to the underneath side of the sole and having a vertical forward edge inclined laterally in a rearward direction from its inner to its outer end in conformity with the axes of the respective metatarsal joints, the pad situated on the insole so that its vertical forward edge exerts pressure on the first metatarsal bones immediately in rear of the metatarsal joints. 75

2. In a metatarsal arch support, the combination of an insole, of a pad of resilient material having a vertical forward edge, said pad being suitably secured to the underneath side of the insole and so situated that its vertical forward edge exerts pressure on the first metatarsal bones immediately in rear of the metatarsal joints. 90

3. In a metatarsal arch support, an insole, 95 and a pad of resilient material of semi-circular shape, the arc of the semi-circle at the rear, said pad raising the forward ends of the bones extending rearwardly from the metatarsal joint.

4. In a metatarsal arch support, an insole and a pad of resilient material of semi-circular shape, the arc of the semi-circle at the rear, the curved edge of the pad beveled or rounded off, and the forward edge vertical 105 and inclined rearwardly from the inner to the outer end, said pad raising the forward ends of the bones extending rearwardly from the metatarsal joint.

LILLIAN ADAIR.
